METHOD OF KNITTING FABRIC

Charles Moses, New York, N. Y.

Application April 26, 1937, Serial No. 138,970

3 Claims.

(Cl. 66—9)

This invention relates to a method of knitting a fleece fabric, double faced fabric or the like on a sinker top knitting machine.

Broadly, it is an object of this invention to knit 5 a fleece or double faced fabric on a sinker top knitting machine, the back of which is composed of inlay threads tied to the loops of the base fabric by a secondary or binding thread known as the weft thread.

Another object of this invention is to produce 10 upon a sinker top knitting machine, a fleece or double faced fabric which is inexpensive to produce at the same time producing a knitted fabric upon which there is less possibility of damage to 15 the cloth in the knitting process.

Another object of this method of producing fleece or double faced fabrics is the ease and speed of production because of the multiplicity of the feeds in the sinker top knitting machine.

Another object of this method of producing a 20 fleece or double faced fabric is to create and produce a larger and infinite variety of patterns due to the multiplicity of feeds on such sinker top knitting machine.

Another object of this method of producing a 25 fleece or double faced fabric is that the needles and other parts of the sinker top knitting machine will have long life and use, and the ease of adjusting such sinker top knitting machine to produce such fabrics will permit a great saving 30 of time and money.

Another object of this method of producing a 35 fleece or double faced fabric on a sinker top knitting machine is that unusual heavy or nub yarns can easily be used as the backing thread, thus creating very heavy fabrics heretofore never knitted on a sinker top knitting machine.

These and other advantages, capabilities and features of the invention will appear from the 40 subjoined detailed description and more particularly pointed out in the claims appended hereto.

In the accompanying drawings, which illustrate a practical embodiment of my invention,

Figure 1 is a perspective view of the portion 45 of a sinker top knitting machine showing needles and sinkers in their proper relationship to receive inlay threads, weft threads and base threads.

Figure 2 is the sinker ring cam used in conjunction with the inlay threads and the weft thread.

Figure 3 is a sinker ring cam used in conjunction with the base thread.

Figure 4 is a top elevation of the sinker dial 55 developed upon a plane, showing sinkers, sinker

cams, needles and threads in proper relationship.

Figure 5 is the inside of the cylinder showing needles, sinkers, carriers and threads in their proper relationship developed upon a plane and one course of the fleece or double faced fabric. 5

Figures 6 to 9, inclusive, are diagrams illustrating each step in the formation of the fabric in the successive steps shown in Figure 5.

Figure 10 is an enlarged view of the grouping of the threads in proper relationship as seen from 10 the fleece face of the fabric.

Figures 11 and 12 are end views of the double nosed sinkers showing the different levels upon which the threads are knitted.

Figure 13 is an end view of a triple nosed sinker 15 showing several knitting levels upon which the different threads are knitted.

Figure 14 is an enlarged view of a knitted fabric knitted with sinkers as shown in Figure 13.

Referring to Fig. 1, sinkers 21 are arranged 20 radially in a circular series. Each sinker is mounted in guides of sinker dial 22 for radial movement under control of a rotary cam ring 20, which has at suitable intervals sinker actuating cams 29 and 30. The right back edges of said 25 cams 29 and 30, acting on the inside of the butts of the sinkers 21 cause said sinkers to recede from P3 as shown in Fig. 11, to the farthest point permissible by cams 29 and 30. The left back edges of said cams 29 and 30 acting on the 30 back edges of the noses of the sinkers 21 cause said sinkers to be pushed from the farthest point permissible by cams 29 and 30 back to P3 as shown in Fig. 11. Between sinkers there are positioned needles 24, such needles moving upwards and downwards in slots in a cylinder 23 of conventional character and such needles having outwardly projecting butts (not shown) adapted to be engaged by means such as stitch cams, rising cams and pattern wheels (not shown) such 35 parts performing the movements necessary in the manufacture of knitted fabrics.

The thread carriers 25 to 28 inclusive, ride above the sinkers 21, said carriers feeding to the needles the different threads used in the manufacture of the knitted fabric. 45

Sinker cam 29 as shown in Fig. 2, is the cam used for sinker movement as shown in Fig. 4, in conjunction with the knitting of inlay thread 31 and inlay thread 32 and weft threads 33, as 50 shown in Fig. 5.

Sinker cam 30 as shown in Fig. 3, is the cam used for sinker movement as shown in Fig. 4, in conjunction with the knitting of the base thread 34, as shown in Fig. 5.

I will now describe my method of producing a fleece or double faced fabric on a sinker top knitting machine by carrying through the knitting process necessary to produce one course of the fleece fabric shown in Fig. 10. For the purpose of illustration, but not in limitation of my invention, I will describe the operation of a unit of six successive needles 24A to 24F, inclusive, as shown in Figs. 5, 6, and 7.

Needles 24A and 24C are elevated selectively to receive inlay thread 31 from thread carrier 25 as shown in Fig. 5. The latches of said needles remain below knitting level L4 so that the previous knitting loops remain on the needle latch. At such point, cam 29, as shown in Fig. 4, actuates sinkers 21 so that inlay thread 31 lies over sinker nose N2, as shown in Fig. 12, between points P1 and P2 as shown in Fig. 11.

Needles 24B, 24D, 24E and 24F do not receive inlay thread 31 and rest at knitting level L4, as shown in Fig. 12, whereas needles 24A and 24C are drawn down by stitch cam (not shown) to knitting level L2 as shown in Fig. 12.

Needles 24D and 24F are elevated selectively to receive inlay thread 32 from the thread carrier 26, as shown in Fig. 5. The latches of said needles remain below knitting level L4 so that the previous knitting loops remain on the needle latch. At such point, cam 29, as shown in Fig. 4, actuates sinkers 21, so that inlay thread 32 lies over sinker nose N2 as shown in Fig. 12, and between points P1 and P2 as shown in Fig. 11.

Needles 24A, 24B, 24C and 24E do not receive inlay thread 32. Needles 24A and 24C remain at knitting level L2 and needles 24B and 24E rest at knitting level L4 (Fig. 12). Needles 24D and 24F are drawn down to knitting level L2 by stitch cam (not shown).

A rising cam (not shown) elevates needles 24A to 24F, inclusive, to receive the weft thread 33 fed by thread carrier 27. The latches of said needles clear level L1, which is the top portion of the sinkers 21, thus clearing the inlay threads 31 and 32 and leaving the previous knitting loops 45 upon the shanks of the needles. All needles are then lowered to level L3 (Fig. 12) thereby causing the closing of the needle latches by the inlay threads 31 and 32, such needles then casting off said inlay threads 31 and 32, but retaining the 50 previous knitting loops upon said needles. At this point sinker cam 29 (Fig. 4) actuates sinkers 21 so that the knitting takes place upon sinker nose N2 at knitting level L2.

A rising cam (not shown) elevates needles 24A to 24F, inclusive, to receive the base thread 34 fed by thread carrier 28. The latches of said needles clear level L1, which is the top portion of the sinkers 21 thus clearing the inlay threads 31 and 32 which are on the back shank of the 60 needles and weft thread 33 and the previous knitting loops remain upon the front shanks of the needles. All the needles are then lowered below knitting level L4 (Fig. 12) thus casting off the weft thread 33, the inlay threads 31 and 32 and 65 the previous knitting loop. At this point, sinker cam 30 actuates sinkers 21 so that the knitting takes place upon sinker nose N3 at knitting level L4, between point P2 and P3.

When weft thread 33 casts off inlay threads 31 and 32, such weft thread winds around the inlay threads as shown in Fig. 8. When the needles are elevated by the succeeding rising cam (not shown), such needles complete the winding around of said weft thread 33 about the inlay threads 31 and 32. When base thread 34 casts off weft

thread 33, inlay threads 31 and 32 and previous knitting loops, as shown in Fig. 9, said weft thread 33 becomes engaged with the loops of base thread 34 although not forming a knitting loop therewith and thus securing the inlay threads 31 and 32 to 5 the base of the fabric.

I will now describe the sinker action in each successive step of the formation of the fabric. When needles 24A and 24C, take the inlay thread 31, and are drawn down by stitch cam (not 10 shown), to level L3, as shown in Fig. 12, sinker cam 29 withdraws sinker 21 so that the nose N1 of said sinker clears inlay thread 31, said inlay thread 31 being held on the nose N2 (Fig. 12) by the needles 24A and 24C. Similarly, needles 24D 15 and 24F hold inlay thread 32 on the sinker nose N2.

When needles 24A to 24F, inclusive, are elevated to receive the weft thread 33, the needle latches clear level L1 and the sinker cam 29 20 pushes the sinker 21 forward so that the inlay threads 31 and 32 are held against the shank of the needles by the throat formed between the nose N1 and nose N2 of sinker 21.

After needles 24A to 24F inclusive, receive the 25 weft thread 33, cam 29 withdraws sinker 21, and nose N1 clears weft thread 33 so that said weft thread 33 casts off inlay threads 31 and 32 held on nose N2.

When needles 24A to 24F, inclusive, are raised 30 to receive the base thread 34, cam 29 pushes sinker 21 forward so that inlay threads 31 and 32 upon nose N2 have been cast off by the weft thread 33 and are pushed over the tops of the needles so that such inlay threads 31 and 32 ride 35 against the back of the shanks of the needles while the weft thread 33 rides against the front of the shanks of the needles. All three threads 31, 32 and 33, remain upon nose N2 and the weft thread 33 is against the front shanks of the 40 needles while the inlay threads 31 and 32 are against the back shanks of the needles.

After needles 24A to 24F inclusive, receive the 45 base thread 34, cam 30 withdraws sinkers 21 so that the nose N2 clears base thread 34 and permits the previous weft thread and inlay threads to drop to knitting level L4 at which point base thread 34 casts off the weft thread 33 and inlay threads 31 and 32.

The previous described consecutive knitting 50 steps can readily be seen in the enlarged needle units of Figs. 6, 7, 8, and 9, corresponding to the knitting of inlay threads 31 and 32, weft thread 33 and base thread 34, respectively.

By a similar method as above described, by 55 utilizing multinoised sinkers, as shown in Fig. 13, in conjunction with sinker ring cams to actuate such sinkers so that the threads drop to different knitting levels, in combination with means to elevate and lower the needles below the different 60 knitting levels, a knitted fabric is produced whereby inlay threads fed at each knitting level are wound around by a weft thread at said level, said weft thread being in turn wound around by the succeeding weft thread and so on until the 65 last weft thread becomes engaged with the loops of the base thread.

Fig. 14 shows such a fabric in which an inlay thread 35 is interlaced by a weft thread 36, which in turn is interlaced by a weft thread 37, said weft thread 37 becoming engaged with the loops of base thread 38 comprising the base of the fabric.

It will be obvious to those skilled in the art that the invention may be embodied in the various types of sinker top knitting machines and that 75

other changes may be made therein. I therefore do not limit myself to what is shown in the drawings and described in the specification but only indicated in the appended claims.

5 The method of producing the above described fabric upon a sinker top knitting machine can utilize spring needles as well as latch needles. I therefore do not limit myself to the type of latch needle described in the specification.

10 I do not limit myself to the above described combination of the number and texture of inlay threads, weft threads and base threads. In other words, one or more inlay threads, one or more weft threads and one or more base threads may 15 be knitted in any combination to produce a wide variety of knitted fabrics.

It is also within the scope of my invention to produce a fabric upon a sinker top knitting machine which has sinkers containing 2, 3 or 20 more levels to the corresponding 2, 3 or more knitting planes.

I claim:

1. A method of knitting a fabric upon a sinker 25 top knitting machine with sinkers having two steps characterized by the following sequence of operations, namely, elevating needles so that the latches of said needles are below the upper step of said sinker, the already formed stitch loops holding said latches against the shanks of the needles, feeding an inlay thread to the hooks of said needles and drawing said needles down so that the hooks are below said step while said inlay thread rests within the throat of said step, elevating needles so that the latches clear said inlay 30 thread, feeding a weft thread to the hooks of said needles and drawing said needles down so that said hooks are below the upper sinker step thus casting off said inlay thread but not the already formed stitch loops while said weft thread rests within the throat of said step, elevating 35 needles so that latches clear said weft thread, feeding a second weft thread to the hooks of said needles, withdrawing said sinkers whereby the already formed stitch loops drop to the intermediate sinker step, drawing said needles down so that said hooks are below said intermediate sinker step thus casting off said first mentioned weft thread but not the already formed stitch loops while said second mentioned weft thread rests within the throat of said intermediate step, elevating needles so that the latches clear said second mentioned weft thread, feeding a knitting thread to the hooks of said needles, withdrawing said sinkers whereby the already formed stitch 40 loops drop to the lowest sinker step, drawing said needles down to cast off said second mentioned weft thread and the already formed stitch loop.

said needles down to cast off said weft thread and the already formed stitch loop.

2. A method of knitting a fabric upon a sinker top knitting machine according to claim 1 wherein in more than one inlay thread is fed to the hooks 5 of the needles at successive feed points to be cast off by the weft thread.

3. A method of knitting a fabric upon a sinker top knitting machine with sinkers having three steps characterized by the following sequence of 10 operations, namely, elevating needles so that the latches of said needles are below the upper step of said sinker, the already formed stitch loops holding said latches against the shanks of the needles, feeding an inlay thread to the hooks of said 15 needles and drawing said needles down so that the hooks are below said step while said inlay thread rests within the throat of said step, elevating 20 needles so that the latches clear said inlay thread, feeding a weft thread to the hooks of said 25 needles and drawing said needles down so that said hooks are below the upper sinker step thus casting off said inlay thread but not the already formed stitch loops while said weft thread rests 30 within the throat of said step, elevating needles so that latches clear said weft thread, feeding a second weft thread to the hooks of said needles, withdrawing said sinkers whereby the already formed stitch loops drop to the intermediate sinker step, drawing said needles down so that said hooks are below said intermediate sinker step thus casting off said first mentioned weft thread but not the already formed stitch loops while said second mentioned weft thread rests within the throat of said intermediate step, elevating needles so that the latches clear said second mentioned weft thread, feeding a knitting thread to the hooks of said needles, withdrawing said sinkers whereby the already formed stitch loops drop to the lowest sinker step, drawing said 35 needles down to cast off said second mentioned weft thread and the already formed stitch loop.

CHARLES MOSES.
